UNITED STATES PATENT OFFICE.

LEE J. VOORHEES, OF BINGHAMTON, NEW YORK, ASSIGNOR TO NATIONAL CARBON COMPANY, INC., A CORPORATION OF NEW YORK.

ELECTRICAL SWITCH.

Application filed May 27, 1921. Serial No. 473,216.

To all whom it may concern:

Be it known that I, LEE J. VOORHEES, a citizen of the United States, residing at Binghamton, in the county of Broome and 5 State of New York, have invented certain new and useful Improvements in Electrical Switches, of which the following is a specification.

This invention relates to electrical 10 switches and has particular reference to an improved switch adapted, when in one position, to be manually depressed into circuit closing relation against the tension of a spring, and, when in certain other positions, 15 is mechanically held either to provide a continuous closure for the circuit or securely out of circuit closing relation.

Switches of the kind described are especially useful in flashlight construction, 20 and the invention will be described in connection with this form of application. It is to be noted, however, that the improved switch may be used in various other electrical devices requiring a simple intermittent circuit closing means, together with provision for continuous operation and security against accidental closing of the circuit.

An object of the present invention is to 30 provide an improved and simplified three-position switch having the capability of operation described. This object is attained, in general, by arranging a conductor strip adjacent the path of a slidable spring 35 pressed contact. The contact is adapted to cooperate with a support, by which it is held in permanent engagement with the conductor strip, and also to be received behind a stop or locking member, out of contact 40 with the strip. When positioned intermediate the support and the stop, the contact is free to be depressed into engagement with the strip, and to be raised automatically to initial position by its spring, when the 45 downward pressure is removed.

A further object is to secure a better and more durable electrical connection between the contact and the conductor strip, by forming the latter so as to present a resilient 50 surface for engagement by the contact when in certain adjusted positions.

The invention will be described more fully in connection with the accompanying drawing, illustrating a preferred embodiment, and in which—

Fig. 1 is a side elevation of a flashlight provided with the improved switch;

Fig. 2 is a vertical longitudinal section on line II—II of Fig. 1;

Figs. 3 and 4 are views similar to Fig. 2, 60 but showing the switch in continuously operating and non-operating positions, respectively;

Fig. 5 is a vertical transverse section on line V—V of Fig. 1; 65

Fig. 6 is an isometric view of the sliding plate member;

Fig. 7 is an isometric view of the base plate; and

Fig. 8 is an isometric view of the contact 70 carrying plate.

Referring to the drawings, reference numeral 1 indicates a flashlight casing having a portion cut away. Above the opening so formed is located an escutcheon plate 2, secured to the casing by rivets 3. The plate 2 has a central elevated portion 4, forming a seat for a slide, indicated generally by reference numeral 5. The slide comprises a tabular surface 6, of slightly greater breadth than the seat 4, and depending lateral flanges 7 adapted to fit over the sides of the seat, for sliding movement therealong. A rim or bead 8 is struck up centrally from the slide; providing a cylindrical receptacle 85 for a push button or thumb-piece which will be described later. Longitudinal slots 9 are cut through the top of seat 4. Shorter slots 10, formed in that portion of the tabular surface 6 lying within the rim 8, are so positioned as to coincide with slots 9 when the slide is fitted upon the seat. 90

The support and locking means previously mentioned are provided on seat 4. Its surface is slit along two lines parallel to 95 and intermediate the slots 9, and the metal included between the slits is bent downward, forming a trough-shaped depression. The flat bottom portion of the depression provides a supporting surface 11, adapted to 100 space a contact member from the plane of seat 4. In a similar way, locking member 12 is formed by depressing the metal surface of the seat along lines at right angles to those of the first depression, and so placed 105 as to align the locking member with the support.

Cooperating with these members is a hollow push button 13 having a convex top 110 and a circular cross section corresponding

in extent to the area included within rim 8. A spiral spring 13' normally retains the button in raised position. The sides of the button are cut away to leave two tongues 14, diametrically opposite, and adapted to pass through the slots 10 in slide 5, thus holding the push button against rotation in rim 8. When so assembled, the slide will be fitted on seat 4, the tongues 14 extending 10 through slots 9, which are of sufficient length to permit the requisite travel of the tongues to carry a circuit closing member, now to be described, into its various adjusted positions.

15 The circuit closing member consists of a plate 15, shown in plan in Fig. 8. The ends of the plate are indented at 16, and the narrowed central portion has a depending and inwardly bent part, forming the contact 17 adapted to cooperate with the support 11 and locking member 12, previously described. The plate is assembled with the other parts by placing the indentations 16 about tongues 14, projecting through coinciding slots 9 and 10, and turning over the ends of the tongues upon the plate, as shown in Fig. 5. In this manner, the push button, slide, and contact plate are clamped in 20 slidable relation to seat 4.

25 A conductive member adapted to cooperate with the contact 17 is illustrated in Figs. 2, 3 and 4, and comprises a metal strip 18 cut away to leave a resilient marginal portion forming a spring contact arm 19 adjacent the support 11, but not extending beneath the locking member 12. It 30 will be understood that the conductor strip 18 may be secured to the inner face of the casing wall in any suitable way and that any desired arrangement may be made for establishing an electrically conductive circuit between one pole of the battery and the conductor strip, and the other pole and the 35 escutcheon plate.

40 The various operative positions of the device are illustrated in Figs. 2, 3 and 4. In Fig. 2, the push button is shown placed for intermittently closing the circuit. The cut 45 away portions of the button are of sufficient extent to leave the clearance 20, permitting depression to bring the contact 17 into engagement with spring arm 19. The air gap between contact and conductor is restored by spring 13' when the depressing force is removed. In Fig. 3, the contact has 50 been depressed and moved along the inclined surface leading to support 11, to rest upon the support, where it is securely held 55 by the resilient pressure of the spring arm 19 and the spring 13'. The contact 17 is 60 reversely bent, as shown, to facilitate its movement into engagement with the spring arm 19. Fig. 4 illustrates the contact 65 locked behind the stop 12. The push but-

ton is pressed downward so that the contact 70 clears the lower wall of stop 12, is moved backward and allowed to spring up behind the stop. This forms an adequate protection against accidental closing of the circuit 75 during shipment or use, for depression of the button cannot bring the contact into engagement with the conductor strip which is cut away adjacent the stop, as shown. To return the button to operative position, it is necessary first to depress it and then move it forward; such combination of movements could hardly occur accidentally.

80 While the combination of switch and resilient conductor strip illustrated is particularly effective, it is evident that either may be used with a correlative part of another form. For example, the spring arm conductor strip may be used with advantage in connection with that type of switch involving only a depressible contact 85 making member. The resilience of the arm makes it possible to secure positive contact at all times, unaffected by wear to which the contact surfaces may be subjected.

90 It is desirable to have a sloping or cam surface leading to support 11, so that the contact may be simultaneously depressed and slid forward to rest upon the support. Evidently, however, if the support had an abrupt approach the contact could still be effectively placed upon it. This, and various other changes in form and relative adjustment of the parts, may be made within 95 the scope of the appended claims.

100 I claim:

1. A switch mechanism comprising a contact arranged to be depressed and to be moved laterally, a spring member separate 105 from the contact and adapted to support the same, means for depressing the contact when said contact is moved laterally, and a conductor arranged to be engaged by the contact when the latter is depressed.

2. The invention according to claim 1 in 110 which the means for depressing the contact includes a cam.

3. The invention according to claim 1 in 115 which additional means are provided for locking the contact out of circuit closing relation to a conductor when moved laterally to another point.

4. The invention according to claim 1 in 120 which additional means are provided for locking the contact out of circuit closing relation to the conductor when moved laterally to another point, the contact being depressible manually at a third lateral position.

5. A switch mechanism comprising a de- 125 pressible and laterally movable push button, a contact rigidly attached to said push button, and cam means for depressing the push button when said push button is moved laterally.

6. In a flashlight, an escutcheon plate provided with a seat, a slide adapted for reciprocating movement on said seat, a push button contact carried by said slide, a conductor strip and inwardly projecting means on the seat for permanently retaining the button contact either in or out of engagement with the strip.

7. The invention according to claim 6, in which a plane surface is provided between the inward projections and adapted to receive the contact portion of the button for intermittent manual operation.

8. A switch mechanism comprising a

relatively extended contact member of 15 elongated form and a relatively restricted contact member spaced therefrom, means for moving said restricted contact over various regions of said extended contact and also beyond its operating surface, and a cam arranged to bring said contacts together when said restricted contact is moved to a position over a particular region of said extended contact.

In testimony whereof I affix my signature.

LEE J. VOORHEES.
